Primary Examiner — Selina Sikder

CLAIM

The ornamental design for a laser module, as shown and described.

DESCRIPTION

FIG. 1 is a perspective view of a laser module showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the laser module where the laser module is in a configuration of use showing portions of the design not visible in the other views.

The broken lines in the drawings depict portions of the laser module that form no part of the claimed design.

1 Claim, 9 Drawing Sheets
